[57] CLAIM

The ornamental design for a display stand, as shown and described.

DESCRIPTION

FIG. 1 is a front, perspective view of a display stand embodying my new design;

FIG. 2 is a front elevational view thereof on a reduced scale;

FIG. 3 is a right side elevational view on a reduced scale, the left side being a mirror image thereof;

FIG. 4 is a top plan view thereof on a reduced scale;

FIG. 5 is a rear elevational view thereof; and

FIG. 6 is a bottom plan view thereof.
